UNITED STATES PATENT OFFICE.

WILLIAM FONDILLER, OF NEW YORK, N. Y., ASSIGNOR TO WESTERN ELECTRIC COMPANY, INCORPORATED, OF NEW YORK, N. Y., A CORPORATION OF NEW YORK.

TRANSFORMER.

1,420,989.

Specification of Letters Patent. Patented June 27, 1922.

Application filed November 15, 1917. Serial No. 202,105.

To all whom it may concern:

Be it known that I, WILLIAM FONDILLER, a citizen of the United States, residing at New York, in the county of New York and State of New York, have invented certain new and useful Improvements in Transformers, of which the following is a full, clear, concise, and exact description.

This invention relates to transformers, and 10 more particularly to transformers or repeating coils for telephone systems wherein both high frequency talking current and comparatively low frequency ringing currents must be efficiently transmitted.

15 In order to effect long distance transmission, such as is now possible, it has been necessary to obtain greater and greater inductance stability in the apparatus used for telephone transmission. Such stability can 20 only be obtained by improving the stability of the magnetic circuit of all the electromagnetic devices, which are used in the system. As is well known, magnetic material of high permeability, such as pure iron or 25 silicon steel, may be subject to large variations in permeability due to varying degrees of residual magnetism therein. In systems heretofore used, such change in the permeability of the core material of the apparatus 30 employed was of little consequence, but in present day systems it cannot be tolerated.

For example, the cores of telephone repeating coils were heretofore composed of a bundle of fine iron wires in ring form or of a pile 35 of thin annular plates. Such coils were sufficient both for the transmission of high frequency talking currents and also for the comparatively low frequency ringing current; but, due to transient currents, which 40 had access to the windings and due also to the comparatively large values of ringing current, which sometimes flowed therethrough, the permeability of the core material to the high frequency talking current 45 varied considerably from time to time and interfered with the stability of the system as a whole and, therefore, with long distance telephone transmission thereover.

The object of this invention is to provide a 50 transformer or repeating coil wherein the tendency of the magnetic circuit to change with respect to currents of telephonic amplitude is substantially overcome without greatly impairing the efficiency of the coil 55 for transmitting both high frequency talking

current and comparatively low frequency ringing current. This result is accomplished by making the magnetic circuit of alternate sections of high permeability and low permeability ferro-magnetic material, that is, of a 60 material whose permeability is substantially greater than unity, the relative length of the sections depending in each case upon the result to be accomplished.

This invention will be more clearly understood by reference to the drawings, wherein:

Fig. 1 shows a repeating coil partly in section embodying this invention, and Figs. 2 and 3 show two forms which the low permeability magnetic material may assume.

In Fig. 1 is shown a repeating coil in which the magnetic circuit is composed of a section 5 of high permeability magnetic material, such as silicon steel where the initial permeability at low magnetizing forces is approximately 500 and a section 6 of low permeability magnetic material such as finely divided iron particles, having an initial permeability at low magnetizing forces of approximately 60, intermediate the 75 ends of section 5. Over this magnetic circuit are wound superimposed windings 7 and 8, which are in inductive relation to each other and constitute inductively connected windings of the repeating coil.

The short section 6 may take either of the forms shown in Figs. 2 and 3. In Fig. 2 it is shown in the shape of a washer and may be composed of finely divided iron particles, individually insulated and formed into a 90 compact mass by high pressure, in accordance with a method described and claimed in the U. S. Patent to Speed, No. 1,274,952, issued August 6, 1918. The modification of Fig. 3 consists of a washer 9, formed of insulating material and of the desired shape, having a plurality of holes 10 therethrough which are filled with a low permeability magnetic material of composition, for example, the same as that used for the washer 100 of Fig. 2.

The advantage of such a composite core is dependent upon the demagnetizing effects of "ends" in a magnetic circuit and upon the decreased reluctance of the low permeability section over what it would be were non-magnetic material used instead of the low permeability material hereinbefore described. The effect of "ends" in the high permeability section is to materially improve its mag- 110

netic stability with respect to telephone currents. Consequently, the impedance stability of the telephone circuit as a whole, is greatly improved. The reduced reluctance 5 of the low permeability section of the magnetic circuit substantially eliminates the tendency for lines of force to leak out of the winding, and, consequently, substantially eliminates any losses from that source in 10 rounding conducting material, as well as crosstalk due to the proximity of other telephone transformers. The effect, then, of this construction results in a highly efficient repeating coil having a stable magnetic circuit 15 with minimum leakage tendencies.

While the invention has been described in connection with a repeating coil having a ring core composed of a long section of silicon steel plates and a short section of finely 20 divided iron, it is to be understood that other materials of similar characteristics can as well be used, and that the form of the sections can as well be other than those shown in the drawings.

25 What is claimed is:

1. A transformer for telephone systems having a core of high permeability silicon steel having a comparatively short gap therein and a spacer of finely divided iron 30 for said gap.

2. A transformer for telephone systems having a composite core of high permeability magnetic material having a transverse gap and a section of low permeability magnetic material located in said gap.

35 3. A transformer for telephone systems having a core comprising alternate long and

short sections, said long section consisting of high permeability magnetic material, and said short sections consisting of low permeability ferro-magnetic material.

4. A transformer for telephone systems having a ring core, a plurality of magnetically coupled windings on said core, said core comprising a comparatively long section of high permeability magnetic material, and a short section of low permeability ferro-magnetic material.

5. A transformer for telephone systems having a ring core, a plurality of magnetically coupled windings on said core, said core comprising a comparatively long section of high permeability magnetic material, and a short section composed of finely divided iron.

6. A transformer for telephone systems having a ring core, a plurality of magnetically coupled windings on said core, said core comprising a comparatively long section of high permeability magnetic material, and a short section of non-magnetic insulating solid material having holes filled with finely divided iron.

7. A transformer for telephone systems having a ring core, a plurality of magnetically coupled windings on said core, said core comprising high permeability magnetic material having a gap and a spacer for said gap comprising finely divided individually insulated iron particles.

In witness whereof, I hereunto subscribe my name this 12th day of November, A. D., 1917.

WILLIAM FONDILLER.
